UNITED STATES PATENT OFFICE

ALBERT C. BLACKBURN, OF MADISON, WISCONSIN

DETACHABLE HEEL

Application filed December 29, 1930. Serial No. 505,448.

This invention relates to certain new and useful improvements in shoe heels and attachments therefor.

One of the principal objects of the invention consists in the provision and arrangement of an attachment of this character to permit ease in the removal and replacement of heels in an effective and expeditious manner through the employment of a simple tool.

With the above and other objects in view, the invention further consists of the following novel features and details of construction, to be hereinafter more fully described, illustrated in the accompanying drawings and pointed out in the appended claims.

In the drawings:—

Figure 1 is a fragmentary side elevation of a shoe heel illustrating by full and dotted lines the relative arrangement of the fastenings therefor.

Figure 2 is a fragmentary bottom plan view of an assembled heel.

Figure 3 is a top plan view of the heel per se.

Figure 4 is a fragmentary side elevation of a heel portion of a shoe with the attachments applied.

Figure 5 is an enlarged detail sectional view taken through the heel portion of the shoe and heel therefor showing the attachment in position to release the heel.

Figures 6 and 7 are perspective views of the component sections of the means of fastening.

Referring to the drawings in detail wherein like characters of reference denote corresponding parts, the reference character 10 indicates generally a shoe upper, 11 the sole therefor and 12 the heel portion; all of the above is of the usual and well known construction and forms no part of the present application for Letters Patent but are mentioned merely for purposes of illustration in bringing forward the novel advantages of the present invention.

The invention primarily resides in the provision and arrangement of a heel 13 having elongated slotted portions 14 in communication with counter-sunk openings 15 of cross section circular formation. Disk members 16,

carried within the body of the heel, and disposed in the manner suggested in Figures 1 and 5 of the drawings, are also provided with an elongated slotted portion 17 designed for alignment with the correspondingly shaped slots 14. Fastening elements in the nature of threaded shanks 18 passed through the registering elongated slots 14 and 17 in the heel and disks respectively, have portions upon diametrically opposite sides thereof flattened, as at 19, and in alignment with the correspondingly disposed portions 20 of the fastening head 21. Said head is slotted or otherwise provided with a kerf 22 for the accommodation of the working extremity of a screw driver or like instrument by means of which the fastenings may be given a quarter turn in either direction to coincide or misalign the heads 21 with the elongated slots 17 in the disks 16. By this arrangement, it is to be noted that heels may be removed and replaced in an effective and expeditious manner through the employment of a screw driver. The present invention overcomes the usual necessity of ripping worn heels from shoes, clipping off the old means of fastenings, such as screws, nails and the like, and the subsequent nailing of the new heels in position for use. The wearer of shoes equipped and constructed in the manner set forth may procure new heels by size or number and apply them himself.

The invention is susceptible of various changes in its form, proportions and minor details of construction and the right is herein reserved to make such changes as properly fall within the scope of the appended claims.

Having described the invention, what is claimed is:

1. A detachable shoe heel construction comprising a heel body having a multiplicity of elongated slots in communication with circular-shaped counter-sunk openings, disk members embedded within the body having slots corresponding in shape and in constant alignment with the elongated slots in the body, and fastenings embedded within the shoe having portions extended through the registering slots to underlie said disks.

2. A shoe heel construction comprising a

heel body having a multiplicity of elongated slots opening toward the upper side thereof and in communication from its under side with circular-shaped counter-sunk entrance openings, disks immovably positioned within
5 the heel body having slots constructed after the manner of and in constant alignment with the elongated slots, and screw fastenings for the heel having the shanks therefor embedded within the shoe and the heads shaped to pass
10 through the registering slots to underlie said disks when shifted a quarter turn.

In testimony whereof I affix my signature.

ALBERT C. BLACKBURN.
